INFANT'S FEEDING SPOON

Edith R. Warren and Owen S. Warren, P.O. Box 107,
Polson, Mont.

Filed Nov. 4, 1957, Ser. No. 694,255

2 Claims. (Cl. 30—327)

The present invention relates to an infant's feeding spoon, especially adapted for use when training small children to eat.

Previously the problems involved in teaching small children to feed themselves have been recognized, and various types of training spoons have been designed and sold.

It is an object of the present invention to present an improved type of infant's feeding spoon of different structure than those heretofore used. In presenting this different type of feeding spoon, it is a further object of this invention to provide a spoon which infants can more readily and easily use.

Other objects and advantages of the present invention will be apparent from the appended description and drawings, in which

Fig. 1 is a top plan view showing features of an embodiment of this invention,

Fig. 2 is a perspective view showing construction of the spoon as viewed from an angle of approximately 45 degrees with respect to a plane along the top surface of the bowl of the spoon, and

Fig. 3 is a side elevation taken at 90 degrees to Fig. 1 showing further details of the spoon construction.

Briefly stated, the present invention provides an infant's training spoon which may be readily gripped by small children and which may be held without assistance by infants, so that they may learn to feed themselves. In order to simplify the feeding operations, the shank of the spoon handle is disposed at an angle with respect to the center line of the bowl both horizontally and vertically, and the spoon handle is bent back under the shank to provide a convenient gripping and automatic positioning feature.

The detailed features and construction of an embodiment of this invention are shown in the accompanying drawings, in which it will be noted that the infant's feeding spoon 11 comprises a conventionally designed bowl 12, the food-holding depression of which is formed by a bottom 13 and a lip 14. As in the usual construction, the upper portion or lip 14 of bowl 12 is disposed along a plane, and the bowl itself is symmetrical about a longitudinal axis passing through the tip 16 and through the fillet portion 17 connecting the bowl 12 to the shank 18.

As shown in Fig. 1, the shank 18 is disposed at an angle greater than 90 degrees with respect to the longitudinal axis of the bowl 12. This angle, which in the present embodiment is approximately 97.5 degrees, has been found to be advantageous, inasmuch as it is desirable to keep the infant's hand away from the bowl a sufficient distance to allow adequate clearance between the hand and the face when the spoon is raised to feeding position.

As shown in Fig. 3, the shank is likewise disposed at an angle greater than 90 degrees with respect to a ver-

2

tical axis through the bowl 12 normal to the plane of the lip 14. In this embodiment, this angle is likewise approximately 97.5 degrees. Here again this angular disposition is provided in order to prevent interference between the child's hand and face.

In order to provide a more adequate gripping member, the handle portion 19 of the spoon 11 is bent backwardly underneath the shank 18 to provide a loop 21 of sufficient size to provide clearance for an infant's fingers 10 between the shank 18 and the handle 19. Further, the end 22 of the handle 19 is bent upwardly toward the shank 18, so that the infant's fingers will be restrained by the end 22, the loop 21, the handle 19 and the shank 18. With restraint on all sides, any tendency of the spoon to tip or tilt as it is being raised to the mouth is minimized.

As a further detail of construction, it should be noted that the handle 19 is bent backwardly toward the bowl 12 of the spoon 11 in such manner that the bottom 13 of the bowl 12 is substantially in the same plane as the bottom surface of the handle 19 when the plane of the lip 14 is horizontally disposed. This makes it possible to set the spoon down on a flat surface, such as a table, without spilling the contents of the bowl.

While the angularity between the shank and the bowl has been shown and described as approximately 97.5 degrees, it is obvious that the angle may be decreased slightly or substantially increased without departing from the scope of this invention. With slight changes in design, angles of from 93 degrees to 120 degrees might be used in conjunction with the other structural features of this invention.

The foregoing and additional features of the present invention are all deemed to be part of this invention insofar as such features are defined in the hereunto appended claims.

What is claimed is:

1. An infant's feeding spoon comprising a bowl inclusive of a bottom and a lip member, a shank joined to said bowl and extending upwardly and outwardly past the confines of said bowl at an obtuse angle with respect to vertical and horizontal axes respectively of said bowl, a handle on said shank looped under the shank and directed backwardly toward and coplanar with the bottom of said bowl, said handle being spaced from said shank a distance corresponding to the size of an infant's fingers, and an upturned portion on the end of said handle positioned for additional confinement of an infant's fingers, said handle, bowl, shank and lip members being cooperatively arranged each to each whereby the plane of said lip members and the plane defined by said handle and bowl bottom are parallel each to each to provide level, outrigger support for said bowl for preventing spillage therefrom when the spoon is placed at rest on a level surface.

2. Structure in accordance with claim 1 in which the obtuse angle between the shank and vertical and horizontal axes of said bowl is approximately ninety-seven and one-half degrees.
